UNITED STATES PATENT OFFICE.

RICHARD VARLEY, OF ENGLEWOOD, NEW JERSEY, ASSIGNOR TO THE AUTOCOIL COMPANY,
A CORPORATION OF NEW JERSEY.

IGNITION SYSTEM FOR EXPLOSION-ENGINES.

No. 885,894.

Specification of Letters Patent.

Patented April 28, 1908.

Application filed November 17, 1906. Serial No. 342,833.

To all whom it may concern:

Be it known that I, RICHARD VARLEY, a citizen of the United States, residing at Englewood, in the county of Bergen and State of New Jersey, have invented certain new and useful Improvements in Ignition Systems for Explosion-Engines, of which the following is a full, clear, and exact description.

My invention relates to ignition systems for explosion engines and includes several features of improvement in apparatus of that class having a plurality of induction coils which are respectively connected to different spark plugs of a multiple cylinder engine.

15 The main object of the invention is to provide a very compact and convenient construction of so-called timer or circuit controller, which is adapted to be placed on the usual vertical shaft for this purpose in an automobile, and which controls the ignition circuits of the various coils with absolute precision and efficiency; in other words, the times of opening and closing the circuits are arranged to be absolutely definite with respect to the 20 engine cycle for any adjustment in spite of the vibration of the circuit controller or other unfavorable influence. The circuit closure is also adapted to be efficiently made notwithstanding grease and oil within the 25 circuit controller for the usual lubrication purposes.

A further object of the invention is to enable the use of a dynamo or magneto generator and a battery as alternative current 30 sources, and to insure the battery against being left short circuited when the engine is not running.

With these and other objects in view, the invention consists in the features of construction and combination hereinafter set forth and claimed.

In the drawings: Figure 1 is a transverse sectional view of a circuit controller embodying the principles of my invention; this 45 section is taken on the line 1—1 of Fig. 4; Fig. 2 is a detail view showing the revoluble part or element; Fig. 3 is a top view of the same; Fig. 4 is a vertical sectional view; Fig. 5 is a diagrammatic representation 50 showing the electrical circuits.

In order to properly control the ignition circuit of an explosion engine, it is necessary to have an absolutely definite time at which the primary circuits of the various induction coils are opened and closed. In the case of

dynamo ignition, it is important to have a definite time of opening the circuits, and in case of battery ignition, of closing the circuits, in order that definiteness of firing in the engine cylinders may be obtained. In order 60 to secure this result I make use of separate circuit closing and circuit opening means, and further provide an adjustment by which their relation to the engine cycle may be modified. This is of course variable in use 65 by swinging the entire circuit controller frame through a limited angle, and the purpose of the special or additional adjustment above mentioned is to accord the control of the circuits most advantageously to the arc 70 of throw of the circuit controller casing, in order that the best range of control can be attained in driving.

In carrying out the invention I also aim to secure very great rigidity and freedom from 75 vibration of the circuit controlling parts, so that the timing will be absolutely accurate, notwithstanding very high speeds of the engine.

Referring to the drawings in which like 80 parts are designated by the same reference sign, 1 indicates a frame or casing which has a lower flanged edge 2, with arcuate slots therein of the ordinary form, and which need not be particularly shown.

85 3 indicates studs projecting upwardly from a fixed support 4, through said arcuate slots, and having springs 5, and washers 6 thereon, to hold the frame or casing 1 in angularly adjustable but non-vibratable relation upon 90 the support 4.

95 7 indicates a shaft revolving commensurately with the engine, and generally known as the half-time shaft, and which projects upward axially through the frame or casing 1. This shaft carries the revoluble element or parts which control the timing of the circuits.

100 8 is a sleeve which loosely fits upon the shaft 7, and which has a plurality of flanges 9, 10 and 11, at spaced intervals thereon. On the lower part of this sleeve and immediately adjacent to the bearing 12, there is formed a cam 13, which is integral with the sleeve. The bearing 12 is designed to accurately 105 guide the rotation of the half time shaft 7 within the frame or casing 1, so that by this means the cam 13 is held efficiently in its central axial relation, no matter how great the speed or vibration of the parts. In other 110

words, the arrangement of having the cam 13 immediately adjacent to the bearing 12 of the casing 1 makes it impossible for any lateral or eccentric movement of the cam to take place, even if the circuit controller as a whole should vibrate. This is a feature of very great practical importance, because in motor vehicles there is a great deal of vibration, and unless some means like the foregoing is provided, the circuit controlling cam will acquire irregular movements which will destroy the accuracy of the ignition. The lower face 14 of the frame or casing 1 has an integral downwardly extending stud 15 thereon, which constitutes a journal bearing for a pivoted arm or finger to coöperate with the cam 13. This arm or finger is particularly shown in Fig. 1, and comprises an arm 16, within the frame or casing 1, and having a roller 17 thereon to coöperate with the cam 13.

18 indicates another arm of this circuit breaking lever or finger. The arm 18 lies wholly outside of the frame or casing 1, and 25 the only connection between the arm 18 outside the casing and the arm 16 within the casing, is the pivot connection extending through the stud or journal 15.

19 denotes an insulated stud or contact on 30 the arm 18 outside of the casing, and 20 indicates a fixed contact supported by, but insulated from an extension 21 of the main frame or casing.

22 designates a spring which impels the 35 vibrating lever, so that the roller 17 is moved into the path of the cam 13.

By this construction it will be observed 40 that the contacts 19 and 20 are wholly outside of the circuit controller casing, so that they are kept bright and clean and free from the oil and grease which is necessarily present on the inside of the circuit controller.

Between the flanges 9 and 10 of the sleeve 8 there is pivoted on a stud 23, a finger 24, 45 carrying at its extremity a roller 25, spring pressed outward by compression spring 26. The interior of the frame or casing 1 is lined with insulating material 27, and in this insulating material are inset a plurality of segments 28, each of which lies in the path of the roller 25 in its angular movement.

29 denote threaded extensions of the segments 28, which serve to hold said segments in place, and also to form terminals for the 55 connection of the circuit wires to the various induction coils.

On the upper face of the flange 10 there are provided a plurality of studs 30, to each of which is pivoted a finger 31, carrying a 60 roller 32.

33 indicates springs which are arranged to normally press the rollers 32 inward. These rollers lie in the same horizontal plane as a metallic ring 34, which is embedded in the 65 insulating material 27. The rollers 32 are

out of contact with the ring when the apparatus is stationary, but when the engine is running, they fly outward by centrifugal force and contact with the ring 34, to establish a continuous electrical circuit there- 70 with.

The upper flange 11 of the sleeve 8 forms part of a special means which I employ for fixing the sleeve 8 in any desired angular relation on the half time shaft 7. For this 75 purpose the upper face of the flange 11 is annularly crowned or toothed, as clearly shown at 35, in Fig. 2.

36 denotes a collar which is splined to the half time shaft 7 so as to be capable of longitudinal but not relatively rotatable movement thereon. This collar is also toothed or crowned, as shown at 37, and the crowns 35, 37, are capable of meshing with one another in any desired angular relation. 38 denotes 85 a cotter pin passed through alined holes of the shaft 7 and the collar 36. In order to operate this adjustment it is merely necessary to withdraw the cotter pin 38 and lift the collar 36 slightly on the half time shaft 90 so as to disengage the crowns 35, 37. The sleeve 8 is now free to be moved into any desired angular position with respect to the shaft 7. When it is in the proper position, the collar 36 is again depressed so as to re- 95 engage the crowns 35 and 37, after which the cotter pin 38 is again inserted to lock all the parts together.

Referring now particularly to Fig. 5, I will describe the operation of the device and 100 the electrical circuits and connections which I employ. D indicates a dynamo, and B a battery, which have their potential terminals respectively connected to the switch contacts *c*, *c'*. The dynamo D is permanently 105 grounded at *G*, while the battery may be grounded at *G'*, by a push button *X*, which, however, normally serves to break this ground connection. This terminal of the battery is, however, permanently connected 110 to the ring 34. The switch arm *C* is in electrical connection with the vibrator contact 19 by wire *l'*, and a wire *l* connects the contact 20 with the primaries of induction coils *I'*, *I*, *I*³ and *I*⁴. The secondaries of 115 these coils run to the spark plugs and to ground in the usual way. From the various induction coil primaries there are connections made to the segments 28 by means of wires *h'*, *h*², *h*³ and *h*⁴. By the above arrangement the switch *C* may be manipulated 120 to connect either the dynamo or battery potential terminals to the induction coils, and this circuit is intermittently completed and broken by the rotation of the half time 125 shaft. When the roller 25 is passing on to any one of the segments 28, the circuit is completed at the points 19 and 20, so that a complete circuit is formed from dynamo D, through switch arm *C*, wire *l'*, contacts 19 130

and 20, wire l^2 , primary coil I^3 , wire h^3 , segment 28, and roller 25, to ground. Before the roller 25 leaves the segment 28, cam 13 becomes effective to impel the roller 17 outward, so that the circuit is abruptly broken between the contacts 19 and 20, so that injurious sparking is largely avoided. These contacts are of platinum or non-fusible metal, and the cam impelled separation is quick and positive. In adjusting the time of the ignition by angularly moving the circuit controller casing 1, it is evident that since the segments 28 and the vibrator arm 16 move together, the current duration or primary dwell will not be changed.

At all times when the engine is at rest, the rollers 32 move initially under the influence of their springs so as to break contact with the ring 34, so that there is no possibility of the battery being left in a closed circuit position, so as to become uselessly exhausted.

By the above construction it will be noted that the circuits are positively and precisely controlled in use, and efficient contact is insured, notwithstanding oil and grease within the circuit controller casing. As shown in Figs. 1 and 4, the contact 19 on the arm 18 projects upwardly from such arm, so that the point at which the circuit is broken is entirely above the plane of any oil which may spatter out of the bearings of the circuit controller casing. In practice this is a feature of importance, because there is considerable oil sprayed around in a horizontal plane at the base of the circuit controller, which might get on the contacts and interfere with the circuit, if this were not provided against.

0 What I claim, is:—

1. In an ignition system for explosion engines, a shaft having a sleeve angularly adjustable thereon, a plurality of rollers carried by said sleeve, and metallic conductors concentric with said shaft in the path of said rollers, certain of said conductors being connected into the primary circuits of a plurality of induction coils to periodically interrupt such circuits when the engine is running and centrifugal means coöperating with the remaining conductor to permanently interrupt the circuits when the engine is at rest.

2. In an ignition system for explosion engines, a sleeve having a cam integral therewith and a pair of flanges, a finger journaled between said flanges, a roller on said finger, segments in the path of said roller, a circuit breaking lever in the path of said cam, and circuits including said lever and said conductors and the primaries of a plurality of induction coils.

3. In an ignition system for explosion engines, a shaft having a sleeve angularly ad-

justable thereon, a cam integral with said sleeve, a circuit breaking lever in the path of said cam, a pair of flanges integral with said sleeve adjacent said cam, a finger having a roller carried by said flanges, a plurality of segments in the path of said finger, and a plurality of induction coils having their primaries in circuit with said lever and said segments.

4. In an ignition system for explosion engines, a plurality of non-vibrator induction coils each having a primary winding, said primary windings having one common terminal, a circuit controller having a plurality of segments respectively connected to the other terminals of said primary windings, a permanently grounded arm rotatably engaging said segments, a circuit opening device including a cam-impelled lever connected to the circuit of said common terminal, a dynamo and a battery, and means for connecting the potential terminal of either to said circuit-opening device, centrifugal means for grounding the battery when the engine is running, and a separate push button for grounding the battery whenever desired, said battery being normally ungrounded.

5. In an ignition system for explosion engines, a sleeve having a plurality of integral flanges, one of said flanges being toothed or crowned, fingers pivoted between adjacent flanges and spring impelled with respect to said sleeve, means in the path of said fingers for opening and closing the primary circuits of a plurality of induction coils, and a collar having a toothed or crowned edge coöperating with the toothed or crowned edge of said flange for fixing said sleeve in different phase relations to the cycle of the engine.

6. In an ignition system for explosion engines, a frame or casing having a bearing therein, a shaft projecting through said bearing, a sleeve on said shaft, circuit closing and breaking means carried by said sleeve, a cam located between said means and said bearing, and a circuit breaking lever extending through the wall of the casing and acted on by said cam.

7. In an ignition system for explosion engines, a casing having a rigid bearing, a shaft projecting through said bearing, means revolving with said shaft for breaking and completing a plurality of circuits, a cam carried by said shaft between said means and said bearing, and a circuit breaking lever in the path of said cam and extending through the wall of the casing.

In witness whereof, I subscribe my signature, in the presence of two witnesses.

RICHARD VARLEY.
